(57) **CLAIM**

The ornamental design for a saddle and tack bag, as shown and described.

DESCRIPTION

FIG. 1 is a perspective view of a saddle and tack bag of the present invention, a wheeled carrier for receiving the saddle and tack bag of the present invention being shown in phantom for illustrative purposes only and therefore forming no part of my claimed design.

FIG. 2 is a front elevational view of the saddle and tack bag of FIG. 1.

FIG. 3 is a left side elevational view of the saddle and tack bag of FIG. 1.

FIG. 4 is a right side elevational view of the saddle and tack bag of FIG. 1.

FIG. 5 is a rear elevational view of the saddle and tack bag of FIG. 1.

FIG. 6 is a top plan view of the saddle and tack bag of FIG. 1; and,

FIG. 7 is a bottom plan view of the saddle and tack bag of FIG. 1.
